ATTORNEYS

UNITED STATES PATENT OFFICE.

JOHN SNEEGROW BACHMAN, OF ROME, GEORGIA.

TWISTER.

Application filed October 25, 1921. Serial No. 510,237.

To all whom it may concern:

Be it known that I, JOHN SNEEGROW BACHMAN, a citizen of the United States, and a resident of Rome, in the county of Floyd and State of Georgia, have invented certain new and useful Improvements in Twisters, of which the following is a specification.

My invention relates to improvements in 10 twisters, and it consists substantially in the construction, combination and mode of operation herein described and claimed.

One of the objects of the invention is to provide a separator for keeping the many 15 strands of yarn divided in the operation of twisting the strands into a thread.

A further object of the invention is to provide the combination of the invention with the mechanically driven rolls of a twister.

20 Other objects and advantages will appear in the following specification, reference being had to the accompanying drawing, in which:—

Figure 1 is a perspective view of a portion 25 of a twister, illustrating the application of the improved strand separator, and

Figure 2 is a detail perspective view illustrating the combination of the improved 30 separator with the mechanically driven rolls.

35 Referring to Figure 1 of the drawings, it is to be observed that the creel 1 carries a plurality of spindles 2 on each of which spools 3 of yarn are supported. A certain number (three in the first instance) of 40 strands of yarn are to be twisted or combined in a single thread T and wound on a bobbin 4. It is the purpose of the invention to keep the strands of yarn separated, thereby preventing the yarn from running together and tangling.

45 Loops 5 gather or combine the diverging strands of yarn y into a single strand T. This strand is wrapped around the mechanically driven rolls 6 and 7 a number of times as shown in Fig. 2, the rotational movement of the rolls causing the twisting of the single strands of yarn into the resultant thread which is wound on the bobbin 4 as explained above.

50 A bar or separator 8 has a plurality of series of pins 9 which are equal in number to the wraps of the yarn around the rolls 6 and 7. Each bar 8 (for a number are used in

longitudinal alinement) has a head 10 arranged in such a manner that a screw 11 55 may serve to hold the bar in place on the twisting machine.

The bar 8 may be made of steel, or of any other suitable material, and of a size to suit the purpose intended. Or the bar may be 60 made of sheet steel, with slits through the top so as to provide channels or grooves to separate the yarn which is wrapped around the revolving rolls 6 and 7.

The operation is doubtless understood 65 from a reading of the foregoing description, but on a brief review, may be described as consisting of encasing the bar 8 between the mechanically driven rolls 6 and 7 which serve to twist the separate strands of yarn y 70 into the single resultant thread T. This thread is wound on the bobbin 4. The yarn is wrapped around the rolls 6 and 7 a number of times and with sufficient tightness to prevent sagging and insure the twisting action referred to. The pins 9 function to 75 keep the various strands separated so as to prevent tangling.

This arrangement of separating means is regarded as being far superior to the now 80 common expedient of placing idle loose presser rolls on the yarn between the rolls 6 and 7. An objectionable happening of frequent occurrence with this last arrangement is the soiling of the yarn by oil and 85 dirt. Obviously the soiling of the yarn cannot occur with the present separator arrangement. Should the yarn break at the bobbin 4, the strands across the rolls 6 and 7 will remain stationary, since the breaking of 90 the thread at the bobbin automatically releases the pull on the strands and also releases the friction of the yarn on the rolls.

While the construction and arrangement of the improved strand separator herein described and claimed, is that of a generally preferred form, obviously modifications and changes may be made without departing from the spirit of the invention or the scope of the claims.

I claim:—

1. In combination with revolving twister rolls, a bar disposed between the rolls having a plurality of pins separating strands of yarn run across the rolls from one to the other.

2. In combination with twister rolls, a bar disposed between the rolls being of a thickness approximately of or less than the diameter of the rolls, having a plurality of series of spaced fingers for separating strands of yarn wrapped from one roll to the next.
3. A bar, means at each end of the bar by which it may be attached to a machine frame

between revolving twister rolls, so as to constitute one member of a series of such bars 10 along the rolls, and means arranged in a plurality of groups along said bar to produce channels for the passage of yarn from one roll to the next.

JOHN SNEEGROW BACHMAN.
